DESIGN FOR A COMBINED NECKLACE,
ARMBAND, AND BRACELET

Ernie Ralph Orsatti, Los Angeles, Calif.

Application March 19, 1947, Serial No. 137,739

Term of patent 7 years

(CL. D45—16)

To all whom it may concern:

Be it known that I, Ernie Ralph Orsatti, a citizen of the United States of America, residing in the city of Los Angeles, in the county of Los Angeles, State of California, have invented a new, original, and ornamental Design for a Combined Necklace, Armband, and Bracelet, of which the following is a specification, reference being had to the accompanying drawing, forming a part thereof.

Fig. 1 is a front perspective view of a combined necklace, armband, and bracelet disclosing my new design;

Fig. 2 is an enlarged edge elevational view of the bracelet member, with the major portion of the chain broken away for illustrative purposes; and

Fig. 3 is a front elevational view of the bracelet member as shown in Fig. 2.

I claim:

The ornamental design for a combined necklace, armband, and bracelet, substantially as shown.

ERNIE RALPH ORSATTI.
